(57) **CLAIM**

The ornamental design for a handbag, as shown and described.

DESCRIPTION

FIG. 1 is a front elevational view of the handbag showing our new design;

FIG. 2 is a top plan view thereof, the handles of the handbag being diverted from each other;

FIG. 3 is a right side elevational view thereof, the left side elevational view being a mirror image thereof;

FIG. 4 is a rear elevational view thereof; and,

FIG. 5 is a bottom plan view thereof, the handles of the handbag being diverted from each other.

The broken lines in FIGS. 1–5 show the stitching and are part of the claimed design, and the broken lines in FIGS. 1, 3, 4 and 5 showing supporting legs at the bottom of the handbag are for the purpose of illustrating environment and form no part of the claimed design.

1 Claim, 4 Drawing Sheets
